US0D1034722S

(12) **United States Design Patent** (10) **Patent No.:** **US D1,034,722 S**
(45) **Date of Patent:** **** Jul. 9, 2024**

(54) **PVC PIPE REAMER**

(71) Applicant: **Yuanguo Cheng**, Hunan (CN)

(72) Inventor: **Yuanguo Cheng**, Hunan (CN)

(**) Term: **15 Years**

(21) Appl. No.: **29/934,706**

(22) Filed: **Mar. 27, 2024**

(51) **LOC (14) Cl.** **15-09**

(52) **U.S. Cl.**

USPC **D15/139**

(58) **Field of Classification Search**

Primary Examiner — Darlington Ly

(57) **CLAIM**

The ornamental design for a PVC pipe reamer, as shown and described.

DESCRIPTION

FIG. 1 is a front, top and right-side perspective view of the PVC pipe reamer showing my new design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof;
FIG. 7 is a bottom plan view thereof; and,
FIG. 8 is a rear, bottom and left-side perspective view thereof.

The broken lines throughout the drawing figures depict portions of the PVC pipe reamer that form no part of the claimed design.

1 Claim, 8 Drawing Sheets
